UNITED STATES PATENT OFFICE.

IRVING EYER, OF WILMINGTON, DELAWARE, ASSIGNOR TO THE DELAWARE STAMP MACHINE COMPANY, OF WILMINGTON, DELAWARE, A CORPORATION OF DELAWARE.

STAMPING, DATING, OR NUMBERING MACHINE.

No. 893,470.

Specification of Letters Patent.

Patented July 14, 1908.

Application filed July 23, 1907. Serial No. 385,223.

To all whom it may concern:

Be it known that I, IRVING EYER, a citizen of the United States, residing at Wilmington, Newcastle county, State of Delaware, have 5 invented certain new and useful Improvements in Stamping, Dating, or Numbering Machines; and I do hereby declare the following to be a full, clear, and exact description of the invention, such as will enable others 10 skilled in the art to which it appertains to make and use the same.

This invention relates to certain improvements in stamping, dating or numbering machines; and the objects and nature of the invention will be readily understood by those 15 skilled in the art in the light of the following explanations of the structures shown in the accompanying drawings of what I now consider my preferred embodiment from among 20 other arrangements within the spirit and scope of my invention.

My invention consists in certain novel features of construction and in combinations and arrangements of parts as more fully and 25 particularly set forth and described herein-after.

Referring to the accompanying drawings:— Figure 1, is a side elevation of the stamp. Fig. 2, is an end view. Fig. 3, is a vertical 30 cross section. Fig. 4, is a top plan view of the base plate detached from the frame. Fig. 5, is a detail elevation of one of the spacing rings or washers. Fig. 6, is an end view of the reciprocating yoke detached and partially 35 broken away and showing the disk carrier and disks, an end head being partially broken away. Fig. 7, is a detail sectional view showing the base plate in cross section and a portion of a disk in printing position. Fig. 8, is a detail sectional view through the 40 disk carrier, showing a disk thereon in elevation. Fig. 9, is a sectional view of the yoke, detached, showing the disk carrier in elevation with several disks thereon and shown in 45 section, one leg of the yoke being shown as in the act of being swung out to permit removal of the carrier and the disks therefrom. Fig. 50 10, is a detail cross sectional view corresponding to Fig. 8, but illustrating a modified form of carrier. Fig. 11 is a detail perspective view of the carrier of Fig. 8, showing one spacing ring thereon, and one spring impelled pin or pawl lifted from the longitudinal 55 socket.

The main frame of the stamp as shown in 55 the specific example illustrated, consists of the top cross portion 1, having a central vertical guideway or tubular portion 2, to receive the vertical reciprocating stem or handle of the yoke, the two vertical legs or side 60 bars 3, and the base, bottom or face plate 4.

The side bars 3, are rigid with the ends of the cross portion 1, and are usually longitudinally channeled at their inner faces to form guide or slide ways. For instance, these 65 side bars can be formed by lengths of channel bars.

The frame on one side is shown provided with parallel lateral brackets 5, projecting from and rigid with the side flanges of the 70 side bars 3, to receive the inking attachment. The side flanges of the bars 3, are shown recessed adjacent to the brackets and at the lower ends of the side bars, to permit the free swing of the inking attachment during 75 the operation thereof.

The reciprocating yoke comprises a cross bar or head 6, parallel vertical legs 7, secured to the ends thereof and depending therefrom, and a handle or stem 8, rigid with the cross 80 head 6, and passing up and adapted to reciprocate through the tubular guide 2, and above the guide provided with a usually removable knob 9. The handle contains any suitable spring 10, adapted to yieldingly uphold the 85 yoke in normal position. This spring is shown at its lower end bearing against cross pin 11, carried by tubular guide 2, and passing loosely through a longitudinal slot in the stem or handle. The cross head and legs of 90 the yoke can be formed of channeled metal bars as shown with the upper ends of the legs fitted and secured within the ends of the cross head, and with the legs longitudinally channeled at their outer faces. The yoke 95 legs fit longitudinally within the channels of the frame side bars and are adapted to reciprocate vertically therein.

The type disk carrier is fixed to and extends between the yoke legs and forms the 100 axis on which the type disks are mounted and can be individually rotated. The carrier can be formed with a cylindrical circumferential bearing surface 12, for the type disks, as shown in Fig. 10, or the disk bearing surfaces of the carrier can be formed by spaced flanges 13 as shown in Fig. 8, usually arranged say about ninety degrees apart.

In the form shown in Fig. 10, internal radiating ribs or flanges 120 are employed corresponding to the flanges or ribs 13, but at their outer ends connected by the cylindrical bearing wall to form the tube-like carrier instead of the spider-like or open carrier of Fig. 8.

In the form shown by Fig. 8, the longitudinal flanges extend throughout the length of 10 the carrier and their outer longitudinal edges are arranged in the circle of the inner edges of the type disks.

In both forms of disk carrier, the same is formed at the top with a longitudinal open 15 top groove or socket 14, extending throughout the length of the carrier and the bottom wall or floor of this longitudinal socket is formed with a series of spaced parallel sockets, depressions or spring seats 140, each arranged radially of the carrier and at its upper end opening through the floor of the longitudinal socket.

A series of separate reciprocating parallel spring impelled pins or pawls 15, is arranged 25 in the longitudinal socket 14, radially of the disk carrier, and each pawl is pressed outwardly by its own spring 16, arranged in one of the spring seats 140 and compressed between the end wall thereof and the inner end 30 of its pawl to yieldingly press the outer beveled end of the pawl beyond the circle of the disk carrier. I preferably provide a separate pawl 15, for each disk and a separate spring for each pawl. The pawls are loosely arranged in the longitudinal socket 14, and are 35 guided by the side walls thereof.

The type disks are confined on the carrier and the pawls are confined in the longitudinal socket, by end plates or flat heads 17, secured to and closing the ends of the carrier and of the longitudinal socket. The end heads 17, are of slightly greater diameter than the outer circle of the carrier and project beyond the same and a short distance outwardly 40 45 beside the end type disks thereon. The end heads are interposed between the inner faces of the yoke legs and the ends of the disk carrier and the heads and carrier are shown removably secured to the yoke legs by machine screws 18, passed inwardly through the legs and heads and into the carrier, although any suitable means can be employed for this 50 purpose.

Any suitable number of usually similarly 55 formed and constructed type disks 19, can be arranged on the carrier between the end plates or heads. In the specific example illustrated, each disk is in the form of a flat ring or annulus formed of any suitable material 60 having the radially projecting spaced printing type or character closely arranged around the periphery thereof. The central opening of each disk is of a diameter to receive the disk carrier so that the disks will all be prop-

erly centered on said carrier, and whereby 65 said disks can be independently turned or rotated on the carrier as a center.

In the specific example illustrated, the inner edge of each disk is formed with usually 70 V-shaped notches or depressions 20, to receive the locking or holding end of one of said pawls projecting from the carrier. These notches 20, are in number equal to the number of type and are spaced to correspond to the printing type so that a type of the disk 75 will always be presented at the printing point when the pawl is in a notch. Each disk can be provided with any suitable printing characters, such as the letters of the alphabet, the punctuation marks, and the numerals from one to naught, although I do not so wish to limit my invention, whereby through manipulation of the various disks, any desired combination of letters and printing characters can be presented at the printing 85 position to imprint the desired matter in a line.

Suitable means can be provided to space or separate the disks. For instance, I show thin flat spacing rings or liners 21, loosely mounted on the carrier and interposed between and separating the disks. I show each ring formed with a radial inwardly extending projection or tongue 22, loosely projecting into the longitudinal sockets of the 95 carrier to hold the ring against rotation. These tongues serve the further purpose of properly guiding, separating and spacing the spring impelled disk locking pins or pawls and confining each pawl to a position included within the plane of its disk so as to always bear outwardly against the inner edge of its disk and snap from notch to notch as the disk is turned on the carrier to bring the desired character to the printing point. 100 105

The flat horizontal face or base plate 4, is rigidly secured to the lower ends of the frame side bars by any suitable means. For instance, I show the ends of the plate formed with flat vertical ears 40, engaging and removably secured to the flat outer vertical faces of said side bars by screws 41.

I provide one or both ends of the base plate with an outwardly projecting horizontal indicating pointer 42, which in the specific 115 example illustrated, is formed by cutting a tongue from the flat sheet and bending the same down to project beyond the base end and about in the horizontal plane thereof. This pointer is arranged in the plane of the 120 printing line and is adapted to rest on the paper or other material to be imprinted and accurately indicate the line along which the stamp will print. In other words, the end pointer or pointers 42, are arranged at the 125 central longitudinal line of the base plate and beyond the ends of the longitudinal central slot 43, of said plate through which the sur-

face to be imprinted is exposed, and through which slot the disk characters in the printing position project to imprint said surface.

In the specific example illustrated, I show 5 the base plate formed with two slots 44, on opposite sides of and parallel with and close to the central slot 43 to receive the disk printing characters immediately adjacent to the characters in the printing position or line 10 so that when the yoke is depressed to printing position, the characters in the printing position can project the required distance down through the slot 43 without causing adjacent disk printing characters to strike 15 the top surface of the base, as said adjacent characters can move down into the recesses or depressions formed by said adjacent slots 44, see Fig. 7. To prevent said adjacent characters engaging the surface being 20 printed, I show the bottom surface of the base plate provided with a facing 45, of very thin sheet metal or other suitable material bridging the side or adjacent slots 44, and bent or lapped up over the outer side edges 25 of the base plate and the edges thereof forming the central or printing slot 43.

Each printing disk can be independently turned by hand to bring the desired character thereof to the printing point and the 30 dependent pawl or pin of said disk will lock or hold the same in the desired position, irrespective of the remaining disks and without being released or freed by turning any one or all of the remaining disks. If so desired 35 a small flat blade (not shown) can be employed having a flat or chisel like end to engage the disks between the teeth thereof, and turn or rotate the same.

In the specific example illustrated, I show 40 an automatic inking attachment comprising an elongated horizontal open top metal pan or holder 24, removably containing the inking pad 25. The pan and pad are in length not less than the length of the row of type 45 disks, and the pan is carried by two curved vertical arms 26, at their lower or outer ends rigidly secured to the ends of the pad holder, and at their upper portions connected by transverse or horizontal pivot pins 27, to the 50 outer ends of the brackets 5. The upper portions of the arms are parallel with and arranged at the inner faces of the brackets 5, and are formed with inwardly and downwardly inclined extensions 28, arranged between the brackets 5 and the outer faces of 55 the end plates or heads of the disk carrier. The extension 28, of each arm is formed with a downwardly and inwardly inclined elongated cam slot 29, at its upper end terminating in a 60 straight horizontal portion 30, just in rear of the pivot 27. The end heads of the carrier are provided with rigid pins or studs 31, projecting outwardly through said slots.

The arrangement is such that when the 65 yoke and printing devices carried thereby,

are in their normal raised positions, the studs 31, will lie in the horizontal lateral extensions 30, of the slots, and will thereby exert an upward pull on the upper lateral ends of the pad holder arms hence tending to raise the 70 lower ends of said arms and forcing the inking pad upwardly against the row of type printing characters that are located in the printing position.

When downward pressure is exerted on the 75 yoke to move the same and the printing disks down to perform a printing stroke, the studs 31, will press down on the lower edges of the horizontal slot extensions 30, and thereby depress the upper lateral ends of the pad 80 holder arms, swinging the lower ends of said arms outwardly to carry the pad to one side and out of the path of movement of the descending type disks. The arms thus swing outwardly until the slots 29, assume a vertical position, so that the studs 31, can move down the lengths thereof and thus hold the arms and pad in withdrawn position during 85 the printing stroke. When the yoke makes its upward or return stroke, the studs pass 90 up through the slots 29, and when the studs reach the lateral ends 30, of the slots, the pad holder arms are thereby swung to normal position with the pad engaging the type as hereinbefore described. If so desired one 95 pad holder arm only, can be provided with the slotted upper extension.

The disk carrier is provided with concentric end lugs or trunnions 130, rigid therewith and removably projecting through the end 100 heads and into the legs 7, of the yoke to maintain the carrier properly positioned and centered in the yoke. Hence in order to render the carrier readily removable from the yoke, or the type disks readily removable 105 from the carrier for purposes of assembling, repairing or replacing, I secure one or both of the legs 7, in the cross portion 6, of the yoke, to permit outward swing of said leg or legs when the screws 18, are removed, such a distance as to clear the trunnions 130 and permit removal of one or both end heads 17.

In Fig. 9, I show one leg 7, at its upper end mounted on transverse pivot 70, so that when the yoke is slipped from the frame and screws 18, are removed, said leg can be swung outwardly and upwardly so that the end head 17, can be removed and the disks 19, and rings 21, and the pawls can be slipped from and replaced on the carrier.

It is evident that various changes might be resorted to in the forms, constructions and arrangements of the parts described, and that parts might be omitted or elements added, without departing from the spirit and 125 scope of my invention as defined by the claims, and hence I do not wish to limit myself to the exact structures shown.

What I claim is:—

1. In a hand stamp, in combination, a 130

frame comprising side channel bars with in-turned longitudinal flanges, a reciprocating yoke comprising channel bar legs fitted and adapted to reciprocate in the channels of 5 said side bars, type disks, and a disk carrier between and secured to the flat faces of said legs.

2. In a hand stamp, in combination, a frame comprising side bars flanged to form longitudinal channels at the inner sides thereof, and 10 a reciprocating yoke provided with type disks and having depending legs confined and sliding in said channels and having longitudinal outturned flanges between the 15 flanges of said side bars.

3. A hand stamp comprising a type disk carrier formed with longitudinal radiating ribs or flanges spring impelled radial pawls arranged in one of said flanges, type disks arranged on 20 the carrier and at their inner edges yieldingly engaged by the outer ends of said pawls, end heads or plates closing the ends of said carrier to confine the disks thereon, and a reciprocating yoke between the legs of which said 25 end heads and carrier are secured.

4. A stamping machine comprising a frame, a reciprocating yoke having a movable leg, a type disk carrier arranged between the yoke legs and having end lugs removably 30 entering said legs, type disks removably arranged on said carrier, and means removably securing the yoke legs to and the carrier between the same.

5. A stamping machine comprising a reciprocating yoke having depending legs, one 35 of said legs being pivotally mounted to swing outwardly, a type disk carrier secured between said legs and having end lugs projecting into said legs, type disk arranged on said 40 carrier, and means removably securing said pivotally mounted leg to said carrier.

6. In a stamping machine, in combination, a main frame having vertical side bars longitudinally channeled at their inner faces, a 45 reciprocating yoke comprising a cross head and vertical legs at their outer sides having longitudinal flanges fitting and sliding in said side bar channels, a type disk carrier between and secured to said legs and having 50 end studs fitted therein, and type disks on said carrier.

7. In a stamping machine, in combination, a main frame, a reciprocating yoke therein comprising a channel bar cross head, channel bar legs depending from and carried by 55 said cross bar and at their upper ends inserted in the ends of said bar, a type disk carrier extending between and secured to said legs, and type disks confined on said carrier.

8. In a stamping machine, in combination, a main frame, a reciprocating yoke having channel bar legs, a type disk carrier between 60 said legs and having end studs projecting through said legs into the channels thereof, type disks on said carrier, end heads, and se-

curing means passing through said channel bars between the flanges thereof and through said heads and into said carrier.

9. In a stamping machine, in combination, a main frame having side bars longitudinally 70 channeled at their inner faces, a reciprocating yoke comprising legs throughout their lengths fitted and sliding in said channels, a type carrier between said legs and having end studs entering the same, securing means 75 fixing said carrier to said legs, and type disks on said carrier.

10. In a stamping machine, in combination, a main frame having longitudinally flanged channel side bars, a reciprocating 80 yoke having channel bar legs sliding within said side bars, the side flanges of said channel bar legs and side bars longitudinally overlapping in sliding engagement, a type disk carrier arranged between said legs, means removably securing said carrier to said legs, and type disks removably arranged on said carrier, substantially as described.

11. A stamping machine, comprising a yoke having legs formed with perforations, 90 a type disk carrier arranged removably between said legs and having end centering studs removably entering said perforations, removable type disks on said carrier, removable screws relatively securing the carrier 95 and legs, and means whereby said carrier studs can be freed from said perforations, after removal of said screws, to permit removal of said carrier from said legs.

12. A stamping machine comprising a 100 yoke having legs, a type disk carrier arranged between said legs and normally fixed thereto, type disks on said carrier and longitudinally removable therefrom, one of said legs being relatively movable from said carrier to expose the end thereof and permit removal of said type disks therefrom, and means normally securing said movable leg to said carrier, substantially as described.

13. A stamping machine comprising a 110 yoke having legs, a type carrier between and carried by said legs and having rigid end studs removably entering said legs, type disks movably arranged on said carrier and removable longitudinally therefrom, end 115 heads removably arranged on said studs and interposed between the carrier ends and said legs, and removable securing means between said legs and carrier ends, substantially as described.

14. In a stamping machine, in combination, a main frame, a reciprocating yoke therein having depending legs, a non-rotating type disk carrier extending between said legs, means securing said carrier to said legs 125 against independent relative movement, said carrier formed with a longitudinal socket open at the outer side, independently rotatable type disks arranged on said carrier and having notched inner edges, radially arranged 130

independent spring impelled disk engaging pawls arranged in said socket, and end heads arranged and secured between said legs and the carrier ends and closing the ends of said 5 socket and confining the disks on said carrier, substantially as described.

15. In a stamping machine, in combination, a main frame, a reciprocating yoke therein comprising legs, a type disk carrier 10 arranged between said legs and carried thereby and formed with a longitudinal open top socket, means securing said carrier to said legs against independent axial movement, independently rotatable type disks centered 15 on said carrier, radially arranged independent spring impelled disk-engaging pawls arranged in said socket, and separate spacing washers arranged on said carrier and separating each disk and its pawl from adjacent 20 disks and pawls, substantially as described.

16. In a stamping machine, in combination, a main frame, a reciprocating yoke having legs, a non-rotating type disk carrier fixed to said legs and having an open longitudinal top socket, independently rotatable type disks removably centered on said carrier, separate spring impelled removable pawls for said disks arranged in said socket, and spacing washers removably arranged 25 30 loosely on said carrier and having radial tongues depending into said socket, and separating each disk and its pawl from contact with adjacent disks and their pawls, substantially as described.

35 17. In a stamping machine, in combination, a main frame, a reciprocating yoke having legs, a type disk carrier formed with longitudinal radial webs and with central end studs, one of said flanges formed with a 40 longitudinal open top and end socket, independently rotatable removable type disks on said carrier, radially arranged spring impelled disk-engaging pawls in said socket, removable spacing means separating each disk from 45 adjacent disks, said studs removably entering said legs, removable end heads between the carrier ends and legs, and securing means between the legs, head and carrier and holding the carrier against axial movement.

50 18. A stamping machine, comprising a frame, a reciprocating yoke having an end stud and provided with rotatable type disks, depending arms fulcrumed to the frame and provided with an ink pad holder, one arm at 55 its upper end having a lateral extension formed with a downwardly and inwardly inclined elongated slot receiving said stud and at its upper end having a horizontal extension extending outwardly toward the 60 fulcrum of the arm and receiving said stud when the pad holder is in normal position, substantially as described.

19. In a stamping machine, in combination, a main frame, a reciprocating yoke ar-

ranged in said frame and provided with 65 printing devices and an end stud, a swinging pad holder normally arranged with its pad engaging the type in printing position and having an upwardly extending end arm fulcrumed to the main frame and at its upper 70 portion formed with an elongated slot receiving a stud and comprising the straight upwardly and outwardly inclined portion at its upper end terminating in the short horizontal outward extension receiving the stud 75 when the yoke and holder are in their normal positions, whereby said stud on starting on its downward movement and on completing its upward movement leaves and enters said extension and thereby quickly 80 throws the arms and holder to inoperative position and returns the same to operative position, and whereby during the remainder of the movement of the stud said holder is held in inoperative position by the vertical 85 position of the straight portion of said slot.

20. A stamping machine comprising a main frame, a vertically reciprocating printing head having end studs, a pad holder normally arranged in operative inking position 90 beneath said head and provided with outwardly and upwardly extending arms at their upper ends fulcrumed to the frame and at the ends of said head having inward extensions terminating and arranged entirely 95 to one side of the longitudinal center line of said head and formed with elongated inwardly and downwardly inclined slots receiving said studs, substantially as described.

21. In a stamping machine, in combination, a main frame comprising channel bar sides having brackets, a reciprocating yoke confined to reciprocate in said sides and having a printing head and end studs, an inking pad holder normally arranged in 105 inking position below said head and provided with end arms extending upwardly and at their upper ends fulcrumed to said brackets and provided with extensions extending inwardly beside the ends of said 110 head and formed with elongated slots receiving said studs, side flanges of said channel bar sides being cut away to receive said arms and the extensions thereof.

22. A hand stamp comprising a main 115 frame having a fixed face or bottom plate formed with a longitudinal open slot at the printing line and with slots on both sides of and parallel with said first mentioned slot, said plate being provided on its under side 120 with a thin metallic facing closing said slots on opposite sides of the longitudinal slot, and a reciprocating yoke provided with rotatable type disks.

23. In a stamping machine, in combination, a main frame comprising side bars, a reciprocating yoke confined therein and provided with a printing head, a bottom or

face plate formed with a longitudinal opening at the printing line and having its ends turned up forming ears, means removably securing said ears to the lower ends of said bars, the ends of said plate having tongues cut therein and bent outwardly to form exterior line pointers projecting from said ears.

In testimony whereof I affix my signature, in presence of two witnesses.

IRVING EYER.
